PRISMATIC PANELING FOR LIGHTING FIXTURES

Carl X. Meyer, St. Louis County, Mo., assignor to Emerson Electric Co., a corporation of Missouri

Filed Jan. 24, 1964, Ser. No. 78,353

Term of patent 14 years

(Cl. D48—16)

FIG. 3

FIG. 4

FIG. 5

FIG. 2

FIG. 6

FIG. 1 is a plan view of a portion of prismatic paneling for lighting fixtures showing my new design, it being understood the design which is shown in each of the eight rectangular units is uniformly repeated throughout the dimensions of the paneling;

FIG. 2 is a fragmentary sectional view taken at line 2—2 in FIG. 1;

FIG. 3 is a similar view taken at line 3—3 in FIG. 1;

FIG. 4 is a further fragmentary sectional view taken at line 4—4 in FIG. 1;

FIG. 5 is a similar view taken at line 5—5 in FIG. 1; and

FIG. 6 is a greatly enlarged fragmentary perspective view of a portion of the panel as seen from below to show

the regressed form of the prisms, the view being taken at random.

The paneling may be of indeterminant exterior dimensions.

I claim:

The ornamental design for prismatic paneling for lighting fixtures, substantially as shown and described.
